CLAIM

The ornamental design for an electronic test meter housing, as shown and described.

DESCRIPTION

FIG. 1 is a front elevational view of an electronic test meter housing showing our new design, the dial and pointer portions shown in broken lines are illustrative only and form no part of the design claimed;

FIG. 2 is a rear elevational view thereof;

FIG. 3 is a left side elevational view thereof, the right side being a mirror image thereto;

FIG. 4 is a top plan view thereof;

FIG. 5 is a bottom plan view thereof.
